(57) **CLAIM**

I claim the ornamental design for the safety razor handle, as shown and described.

DESCRIPTION

FIG. 1 is an upper perspective view of a safety razor handle.

FIG. 2 is a lower perspective view thereof.

FIG. 3 is a rear view thereof.

FIG. 4 is a front view thereof.

FIG. 5 is a left view of FIG. 3.

FIG. 6 is a right view of FIG. 3.

FIG. 7 is a bottom end view thereof; and,

FIG. 8 is a top end view thereof.

The broken lines in the figures depict environmental subject matter only and form no part of the claimed design.
